UNITED STATES PATENT OFFICE.

FREDERICK W. BRIERLEY AND WALTER W. BRIERLEY, OF NEW ORLEANS, LOUISIANA, ASSIGNORS OF ONE-FOURTH OF THEIR RIGHT TO H. N. JENKINS, OF SAME PLACE.

SAFETY-LOCKING RAILWAY-SWITCH.

SPECIFICATION forming part of Letters Patent No. 231,648, dated August 31, 1880.

Application filed March 30, 1878.

To all whom it may concern:

Be it known that we, FREDERICK W. BRIERLEY and WALTER W. BRIERLEY, residents of the city of New Orleans, parish of Orleans, 5 and State of Louisiana, have invented a certain new and useful Improvement in Self-Locking Railway-Switches; and we do hereby declare the following to be a full, clear, and correct description of the same, reference being 10 had to the annexed drawing, making a part of this specification.

This invention relates to certain improvements whereby the operating and locking of the rails is effectually accomplished by means 15 of a single lever and rod.

The nature of the invention will be readily understood by referring to the accompanying drawing, whereon A A' represent the movable or switch rails, which are connected in 20 the ordinary manner by means of stretchers b b'. The rails c c are secured to head-blocks d d', the inner portions of which are provided with level bearings for the switches to slide upon. At suitable distances from the rails 25 these bearings are provided with vertical pins e e', on which are fitted the operating locking-cams F F', having arms g g', that are pivoted to a coupling-bar, H, the latter being connected, either directly or through an intermediate connecting-rod, k, and bell-crank l, with an arm, x, of the target-staff.

The cams are operated by means of a lever,

n, that is keyed or otherwise secured to the target-staff, and which is moved over a semi-circular track, o, that is provided with perforations p, to enable the same to be secured, by means of a pin, t, in either of its extreme positions. 35

We do not desire to confine ourselves to the use of any particular style of stand, as it is 40 evident that any of the frames at present known or used may be employed in lieu of the one shown in the drawing; but,

Having described our invention, which is applicable to the butt-rail as well as the split-rail switch, what we do claim as new, and desire to secure by Letters Patent, is— 45

1. In a railway-switch, the movable rails thereof, actuated in either direction by means of a cam, said cams bearing directly upon the 50 rails and being pivoted to a suitable connecting-rod, substantially as described.

2. In combination with the track and movable rails connected by bars b' b, the actuating-cams F F', bearing directly upon the rails, bar 55 H, and shifting mechanism, as set forth.

In testimony whereof we have hereunto signed our names.

FREDERICK W. BRIERLEY.
WALTER W. BRIERLEY.

In presence of—

J. C. HUBBELL,
P. J. FINNEY.
